CLAIM

The ornamental design for a compound archery bow, as shown and described.

DESCRIPTION

FIG. 1 is an angled isometric view of a compound archery bow, showing my new design;

FIG. 2 is a right side view thereof;

FIG. 3 is a left side thereof;

FIG. 4 is a front view thereof;

FIG. 5 is a back view thereof;

FIG. 6 is a top view thereof; and,

FIG. 7 is a bottom view thereof.

The broken line in the drawings depicts unclaimed portion of the bow only and forms no part of the claimed design.

1 Claim, 5 Drawing Sheets
